DENTAL ENGINE CONTROL

Richard W. Page, Chappaqua, N. Y.

Application September 13, 1946, Serial No. 696,859

4 Claims. (Cl. 32—23)

1.

This invention relates to improvements in dental instruments, and more particularly to provision of improved controls for fluid supplied in conjunction with the conventional hand piece.

An object of the invention is to provide an improvement on the control means for the air supply of a device such as the improved fluid spray means described in my pending applications, Serial No. 511,073, filed November 20, 1943, now Patent Number 2,420,338, and Serial No. 671,784, filed May 23, 1946, which constitute coupling of the air supply valve with the rheostat foot control for the drilling machine itself, whereby the dentist may at the same time control the speed of the drill and the supply of air to the cavity being drilled.

With these and still other objects which will appear in the following full description in mind, the invention consists in the combinations and arrangements of parts and details of construction which will now first be fully described in connection with the accompanying drawing and will then be more particularly pointed out in the appended claims.

In the drawings:

Figure 1 is an elevation of the drill head, drill carrying arm and engine therefor, and of the rheostat foot control, showing my improved air supply valve applied thereto;

Figure 2 shows a longitudinal section of my improved valve means affixed to the rheostat foot control for a drill;

Figure 3 is a plan view of the mechanism shown in Figure 2;

Figure 4 shows, in elevation, my invention as applied to a modified form of rheostat foot control for a dental drill;

Figure 5 shows a modified form of my invention as applied to a third form of rheostat foot control;

Figure 6 is a longitudinal section through the air supply valve control member shown in Figure 5;

Figure 7 is a top plan of the air supply valve control member shown in Figures 5 and 6; and

Figure 8 is a section through another modified form of my improved air supply valve control unit.

The invention is intended for use with a drilling machine of the conventional type including the usual hand piece for receiving a drill, buffer, cleaner, gum massager, grinding or sanding wheel or other dental instrument, mounted on a jointed engine arm 2 attached to a stand or support 3 (shown in part). The hand piece 1 is operated in the usual manner by a motor 4 having electrical connections 5 leading to the foot controlled

rheostat 6, which latter is attached to any convenient electric power outlet by the usual cord and plug 7. Air and water are supplied to the nozzles 10 at the drill head through flexible tubes 12 and 13, as is fully described in my above mentioned application. The water supply through tube 13 is controlled by a hand valve or control located on the hand piece, and is not involved in the present invention, which is concerned with the supply of air to the nozzle 10 through flexible tube 12, control therefor being coupled with the foot controlled rheostat 6 for the drill engine, so that the dentist may, at the same time and with the same foot, control both the operation of the drill and the air supply.

The foot controlled rheostat 6 is of the usual form comprising a substantially cylindrical casing having a pedal or pedals 20 extending radially therefrom and adapted to be moved to the left or right by the foot of the operator to increase or decrease the speed of rotation of the drill engine 4 and consequently of the drill. In the form shown in Figures 1 to 3, the pedals 20 extend outwardly from the casing 6 through circumferential openings 21 near its base. My improved air supply valve, as adapted for attachment to such a drill speed control, comprises a U-shaped member 30 extending diametrically across the top of casing 6, the arms 31 and 32 extending down its sides to the radial pedals 20. A flat spring 34 is attached at one end by a bolt 35 to the under side of the horizontal channel section 33 of member 30, extending substantially the full width of section 33 and pressing downwardly and away from the top wall of section 33. A downwardly extending bolt 36 is attached to the under surface of the spring 34 at the center of member 30, forming a pivotal attachment to the casing 6, whereby the member 30 may be moved pivotally thereon in coordination with the circumferential movement of the pedals 20, about the vertical central axis of casing 6. A threaded sleeve 37 may be provided for bolt 36 for spacing the member 30 and spring 34 from the top of the casing 6.

Arm 31, comprising a pair of downwardly extending flanges, as shown, is pivotally attached to one of the pedals 20 by a pin or belt 40 while the opposite arm 32 carries a U-shaped pedal member or shoe 41 which fits over the other pedal 20, being free for vertical movement with relation thereto. Horizontally extending and slanted flanges 42 are formed on the shoe 41 for downward pressure by the operator's foot.

A plate 38 partially closes the under side of channel section 33 of the member 30 and spring 34 presses against this plate. Flexible tubing 12, through which the air is supplied to the drill

hand piece, enters the member 30 through an opening 39 therein and is threaded between the spring 34 and the plate 38, out through an opening in the plate 38, back through an opening in the plate 38 and again through opening 39, being then connected to a pressure tank 60 or other suitable source of supply for air under pressure. A bulge or extension is formed on the lower surface of the spring 34 where it presses against the tubing 12, serving to compress the tube 12 for cutting off the flow of air therethrough. Upon downward pressure upon shoe 41 by the foot of the operator, plate 38 is moved downwardly away from spring 34, releasing the pressure upon tube 12 and allowing air to flow therethrough to the air nozzle 10. Accordingly, by sidewise movement of his foot against the shoe 41, the operator may control the rheostat and thus the speed of rotation of the drill, and by downward pressure upon the same shoe with the same foot, he may control the supply of air to the air nozzle 10, without interrupting or interfering with his manual operations.

In some cases the rheostat foot control, as shown in Figure 4, may have pedal arms 70 which extend outwardly from the upper portion of the casing 71, being turned downwardly against the sides of the casing and terminating in outwardly extending radial pedals 72. My invention may be very simply adapted for use with such devices by adjusting the length of the downwardly extending arms of my member 30, as indicated in the figure, the construction and operation being otherwise the same.

Some rheostat foot controls for drills are provided with only one pedal member, though being otherwise substantially the same as the above described control devices. A further modification of my invention is illustrated in Figures 5 to 7 for use with such devices. A pedal shoe 80 is provided, similar to the shoe 41 in shape, for attachment to the pedal of the rheostat control unit. An adapting block 81, having a slotted lower end fitting over the top edge of the pedal 79, is attached to the pedal 79 by bolts 82 and 83. Bolt 82 also extends through the shoe 80 which fits over the pedal 79 and block 81, serving as a pivot for the shoe. A spring 84 is located within shoe 80, abutting the top surface of pedal 79 at one end and a pin 85 extending through shoe 80 at its other end, maintaining an upward pressure upon shoe 80. Tubing 12 for supplying air to the air nozzle 10 is run into shoe 80 between adapting block 81 and a second pin 86 extending through shoe 80, around pin 85 and out again to the air pressure supply source, in a manner similar to that described in connection with the preferred form of my invention described above. Upward pressure of spring 84 upon shoe 80 causes pin 86 normally to compress the tubing 12 (see Figure 6) to cut off the supply of air. Downward pressure of the operator's foot upon the shoe 80 releases this pressure upon the tubing 12, allowing free flow of air through the tubing 12.

A further modification of my invention is illustrated in Figure 8 and employs a pedal shoe 80' similar to the shoe 80, which is pivoted upon the pedal 79' of the rheostat control in a similar manner at point 82' and employs an adapting block 81' and spring 84' in the same fashion. However, in this form an electric switch member 91 is attached to the block 81' and pedal shoe 80', being actuated upon exertion of downward pressure upon the latter. The switch 91 is connected by suitable wiring to a solenoid controlled

valve device 95 inserted in the air supply tubing 12. Switch 91, normally held closed by the pressure of spring 84' upon shoe 80', is opened upon downward pressure by the operator's foot upon shoe 80', operating the solenoid valve device and allowing air to flow through tubing 12 to the air nozzle 10.

As will be apparent from the foregoing description, the modified devices of Figures 5 to 8 may be employed with the rheostats of Figures 2 or 4, where preferred, and electric switch and solenoid valve control may be substituted for the direct valve control of Figures 2 or 4, if desired. However, it is preferred to utilize the valve control, as distinguished from the switch control, whenever feasible, since the rate of fluid flow may be regulated by the foot pressure, instead of obtaining a merely on-and-off operation.

What I claim is:

1. In a dental drilling apparatus having a motor driven drill and means for supplying fluid at the drill, and in combination, a drill motor controller having a horizontally movable operating pedal, a fluid valve, and a pivotally mounted shoe on said pedal embodying a fluid valve operating member whereby horizontal pressure by the foot against said shoe will operate said pedal and vertical pressure thereon will operate said fluid valve.

2. In an attachment for supplying fluid at the drill of a dental engine, and in combination, a fluid supply line, valve means therefor, a shoe adapted to fit over a drill rheostat pedal and means for mounting the shoe for pivotal movement thereon for simultaneously and selectively controlling a drill motor and flow of fluid through the supply line with the foot by pressing against the shoe in one direction to operate the pedal and pressing against the shoe in another direction to operate the fluid supply valve.

3. In an attachment for supplying fluid at the drill of a dental engine, and in combination, a fluid supply line, valve means therefor, a valve operating member, means for mounting the member upon a drill motor controller having a controller pedal, and a shoe carried by said operating member adapted to fit over the pedal and move transversely thereof for simultaneously and selectively controlling the drill motor and the flow of fluid by pressure of the foot upon said shoe.

4. In an attachment for supplying fluid at the drill of a dental engine, and in combination, a fluid supply line, valve means therefor, a shoe adapted to fit over a drill motor controller pedal, means for pivotally mounting the shoe thereon, and valve operating means carried by the shoe and operable by pivotal movement thereof, whereby simultaneous and selective control of the drill motor and the fluid supply may be obtained by pressure of the foot upon said shoe.

RICHARD W. PAGE.
